PLASTIC COASTER

Tillman J. Gressitt, Monkton, Md., assignor to
Hedwin Corporation, Baltimore, Md., a corpora-
tion of Maryland

Application May 23, 1951, Serial No. 15,284

Term of patent 14 years

(Cl. D44—10)

To all whom it may concern:

Be it known that I, Tillman J. Gressitt, a citizen of the United States, residing at Monkton, Maryland, have invented a new, original, and ornamental Design for a Plastic Coaster, of which the following is a specification, reference being had to the accompanying drawing, forming part thereof.

Figure 1 is a top plan view of a plastic coaster showing my new design; and Figure 2 is a cross-sectional view thereof taken along line 2—2 of Figure 1.

I claim:

The ornamental design for a plastic coaster, as shown.

TILLMAN J. GRESSITT.
